COLLAPSIBLE STAND FOR CHRISTMAS TREES

Duncan Tong, 23C Robinson Road,
Victoria, Hong Kong

Filed Feb. 21, 1968, Ser. No. 10,662

Term of patent 14 years

(Cl. D35—3)

Fig. 5.

Fig. 6.

Fig. 7.

FIG. 1 is a plan view of a collapsible Christmas tree stand, in accordance with the invention;

FIG. 2 is a front elevation of FIG. 1;

FIG. 3 is a cross-sectional view taken along line 3-3 of FIG. 2;

FIG. 4 is a cross-sectional view taken along line 4-4 of FIG. 2;

FIG. 5 is a plan view of another embodiment of the invention;

FIG. 6 is a cross-sectional view taken along line 6-6 of FIG. 5; and

FIG. 7 is a cross-sectional view taken along line 7-7 of FIG. 6.

I claim:

The ornamental design for a collapsible stand for Christmas trees, as shown and described.
